UNITED STATES PATENT OFFICE.

THEODORE L. VALERIUS, OF FORT ATKINSON, WISCONSIN, ASSIGNOR TO THE CREAMERY PACKAGE MANUFACTURING COMPANY, OF CHICAGO, ILLINOIS.

MILK OR CREAM VAT.

1,823,427.

Specification of Letters Patent.

Patented Dec. 2, 1919.

Application filed September 21, 1914. Serial No. 362,721.

To all whom it may concern:

Be it known that I, THEODORE L. VALERIUS, a citizen of the United States, residing at Fort Atkinson, in the county of Jefferson and State of Wisconsin, have invented certain new and useful Improvements in Milk or Cream Vats, of which the following is a specification.

My invention relates to improvements in vats in which milk, cream or other liquids may be subjected to heating or cooling processes by means of a medium circulating in a coil or pipe within the vat.

One object of my invention is to insure greater efficiency by providing for a more perfect contact between the heating or cooling medium and the inner surface of the pipe through which it circulates.

A further object is to prevent the contents of the coil from leaking into the vat, thereby diluting or destroying the contents of the vat.

A further object is to insure the rapid circulation of the heating or cooling medium in the coil, thereby maintaining a nearly uniform temperature throughout the entire length of the coil and minimizing the difference in temperature between the coil and the contents of the vat, thus preventing burning on the coil and thereby increasing efficiency and making it easier to keep the coil clean and sanitary.

In the prior art the heating or cooling mediums have been forced through the pipes by pressure, whereas in my improved vat I have provided means for drawing the medium through the coil by creating a vacuum. This method removes all air-pockets, insures a free contact between the circulating medium and the surfaces of the pipes and thus secures greater efficiency. Also, inasmuch as the pressure on the coil is from without rather than from within, in the event that a leak should develop in the coil, the contents of the vat would enter the coil and would show in the discharge thereby promptly discovering the leak; while at the same time I obviate the danger of spoiling the contents of the vat by mixing with it the contents of the coil.

I obviate also the danger of the contents of the vat burning on the coil when a heating medium is used, and thus destroying efficiency by insulation, besides imparting a burnt flavor to the milk or cream and mak-

ing it more difficult to keep the vat clean and sanitary.

In the drawings, Figure 1 is a top plan view partly sectional, the central portion of the vat being cut away to shorten the drawing. Fig. 2 is an end elevation of the vat, and Fig. 3 is a detail view of the driving mechanism.

In the form of my invention which I have selected for illustration, a vat 1 is supported by a base 2. A tubular shaft 3 extends longitudinally through the center of the vat and is mounted in bearings at the ends of the vat and supports a pipe coil 4 which has a continuous open connection with the respective end portions of the hollow shaft 3 to permit of the circulation of the heating or cooling fluids through the coil, a baffle 3^a or other suitable means being provided to prevent the fluid from passing directly through the shaft. One end of the tubular shaft 3 is adapted to be submerged in a fluid 5 contained in a reservoir 6 which may be mounted on one end of the vat; the other end of the tubular shaft communicates with a centrifugal pump 7 and through it with a return pipe 8 which discharges into the reservoir 6.

A motor 9 is supported by a bracket 10 mounted on one end of the vat. The motor, through a pinion 11, gear 12, shaft 13, worm 14 and gear 15, imparts a slow rotary motion to the tubular shaft 3 and the coil 4; and through the above mentioned connection and gears 16, 17, 18, 19 and 20, imparts a rapid rotary motion to the pump 7. By means of a shifter-lever 21 and a clutch 22, the pump may be stopped at will without interfering with the revolution of the coil.

The end of the tubular shaft 3 which is submerged in the fluid 5 is surrounded by a strainer 23 to prevent solid matter from entering the coil. A steam pipe 24 passes through the fluid in the tank and discharges into the mouth of the hollow shaft 3 to provide means for introducing a steam jet to heat the fluid before it passes through the coil. The said steam pipe may be carried beneath the vat to the opposite end, for greater convenience in operation.

An inlet 25 and an outlet 26 are provided in the end of the vat for the introduction and removal of cream or milk. A switch-box 27 may be attached to the side of the vat in proximity to the motor. A valved water in-

let 28 may be connected to a source of supply for the purpose of filling the reservoir 6.

In operation, assuming that the vat has been filled with milk or cream and that the reservoir 6 contains a sufficient quantity of the heating or cooling fluid which it is desired to use, the motor is started, causing a very slow revolution of the coil, and at the same time rapidly driving the pump which quickly creates a vacuum in that part of the tubular shaft and coil not already filled with the fluid, thus drawing the heating or cooling fluid through the coil, when it passes through the pump into the discharge pipe 8 and is finally returned to the reservoir 6. If desired, a jet of steam may be injected into the coil by means of the pipe 24.

It will be observed that since there is no connection from the outlet of the return pipe 8 to the inlet of the tubular shaft 3, there can be no closed circulation of the heating or cooling liquids, and the pump, while serving to force the liquid into the return pipe 8 after it passes the pump, actually draws the liquid through the coil by means of the partial vacuum created. In the prior art the liquid has been forced through the coil. This distinction is of the utmost importance, since the method of drawing instead of forcing the fluid through the coil gives greater efficiency, prevents the possibility of water or brine leaking from the coil and hollow shaft 3 into the milk or cream; and if a leak is developed by which the milk or cream enters the coil, it is quickly discovered, as it will be shown in the discharge of the pump. There are numerous other advantages of this construction some of which are referred to at the beginning of this specification.

The rapid flow of water through the pipe coil 4 is highly advantageous in that when steam is admitted through the pipe 24 the rise in temperature of the coil is substantially uniform throughout its entire length.

If the flow of water were slow the rise in temperature would be much faster at the steam-inlet end (the right-hand end as viewed in Fig. 1) than at the other end. During the time that the milk or cream is being brought up to the desired temperature and while it is being held at the desired temperature, there is, of course, a difference between the temperature of the milk or cream and the temperature of the coil, the coil being somewhat hotter. When all parts of the pipe coil are of substantially the same temperature, there is less difference between the temperature of the milk or cream and the temperature of the coil than when one end of the coil is considerably hotter than the other.

It will be evident that when one end of the coil is much warmer than the other, the difference in temperature between the hot end of the coil and the milk or cream in contact with said hot end of the coil will be much greater than the difference in temperature between the cooler end of the coil and the milk or cream in contact with said cooler portion of the coil. When the flow through the coil is so slow that the inlet end heats up more rapidly than the other, said inlet end of the coil becomes hotter than it would if the flow were so rapid as to equalize the temperature throughout the coil. Because of such increased temperature at the inlet end of the coil, the albumen in the milk or cream is coagulated and clings to the hot end of the coil, becoming burned thereon.

It is understood that the particular structure may be varied without altering the spirit of the invention and that I am not to be limited to the precise form of construction shown herein.

I claim as my invention:

1. In an apparatus of the class described, a vat, a reservoir, a pump, a revoluble tubular coil extending longitudinally of said vat and communicating at one end with said reservoir and at the other end with said pump, and a steam pipe extending into said reservoir and terminating at the mouth of the coil to provide for the discharge of a steam jet into the contents of the coil.

2. An apparatus of the class described having, in combination, a vat, a coil in said vat for heating or cooling the contents of said vat, a receptacle containing a heating or cooling medium and communicating with said coil, and means for sucking said medium through said coil at a sufficiently high velocity to maintain the pressure at any point of said coil below the outside pressure at that point.

3. An apparatus of the class described having, in combination, a vat, a hollow element in said vat adapted to carry a temperature-changing medium and means for passing the temperature-changing medium through said element at a pressure less than the pressure of the fluid in said vat, whereby a leak in said member will allow a flow of fluid from said vat into said member so that the contents of said vat are not contaminated.

In testimony whereof, I hereunto set my hand in the presence of two witnesses.

THEODORE L. VALERIUS.
